(57) **CLAIM**

The ornamental design for an adjustable mounting bracket for a hose storage compartment as shown and described.

DESCRIPTION

FIG. 1 is a perspective view of the adjustable mounting bracket for a hose storage compartment showing my new design;

FIG. 2 is a top view thereof;

FIG. 3 is a front view thereof;

FIG. 4 is a bottom view thereof;

FIG. 5 is a rear view thereof;

FIG. 6 is a left-side view thereof;

FIG. 7 is a right-side view thereof;

FIG. 8 is a perspective view of the adjustable mounting bracket for a hose storage compartment of FIG. 1 in a position of use with environmental subject matter;

FIG. 9 is a top view thereof;

FIG. 10 is a front view thereof;

FIG. 11 is a bottom view thereof;

FIG. 12 is a rear view thereof;

FIG. 13 is a left-side view thereof; and,

FIG. 14 is a right-side view thereof.

The broken lines and the areas within them depict portions of the adjustable mounting bracket for a hose storage compartment that form no part of the claimed design.

The additional broken lines shown in FIG.'s 8-14 depict environmental subject matter that forms no part of the claimed design.

1 Claim, 8 Drawing Sheets
